R. F. Bourne

UNITED STATES PATENT OFFICE.

GUSTAV STAIB, OF NEW YORK, N. Y.

CARRIER FOR PACKAGES AND THE LIKE.

No. 839,081.

Specification of Letters Patent.

Patented Dec. 18, 1906.

Original application filed February 10, 1905, Serial No. 245,005. Divided and this application filed December 6, 1905, Serial No. 290,514.

To all whom it may concern:

Be it known that I, GUSTAV STAIB, a citizen of the United States, residing in New York city, borough of Richmond, New York, have invented certain new and useful Improvements in Carriers for Packages or the Like, of which the following is a specification.

This application is a division of my application for patent on store-service apparatus, filed February 10, 1905, Serial No. 245,005; and the object of this invention is to provide improvements in carriers adapted to carry packages and the like, whereby the receptacle or box for supporting goods may readily be raised and lowered so as not to interfere with persons and be in convenient position for inserting and removing goods.

My invention comprises the novel details of improvement and arrangements of parts that will be more fully hereinafter set forth and then pointed out in the claims.

Reference is to be had to the accompanying drawings, forming part hereof, wherein—

Figure 1 is a side elevation of a carrier embodying my invention. Fig. 2 is an end view thereof partly broken, and Fig. 3 is a plan view thereof.

Similar numerals of reference indicate corresponding parts in the several views.

30 The numeral 1 indicates generally a substantially rectangular frame having end members 1^a, provided with yokes 1^b, in which rollers 2 are pivotally supported, said rollers being shown grooved and adapted to 35 travel upon a track, such as an overhead suspended wire or the like, rods 3 connecting the end members 1^a.

At 4 is a receptacle—such as a box, basket, or the like—suspended from frame 1, and I 40 provide means for holding said receptacle elevated when the carrier is not in use and while it is traveling and for permitting the receptacle to be pulled down into convenient position for placing goods in the receptacle 45 and removing the goods therefrom. To this end I connect receptacle 4, preferably near its corners, with chains or other flexible connections 5, which are supported by spring-rollers 6, journaled in the carrier-frame 1.

50 These rollers may be in the nature of well-known shade-rollers having spiral springs 6^a within them and mounted in frame 1 in manner similar to mounting shade-rollers. In

order to compensate for varying tension in the springs of the rollers 6 under varying positions of receptacle 4, I provide these rollers near their opposite ends with cone-like pulleys 7, having spiral or worm-like grooves 7^a, these worm-like cones being shown tapering outwardly or toward the ends of frame 1, the chains being attached to the larger diameter of the cones. This arrangement is such that when the receptacle 4 is pulled down and the springs within the rollers 6 thus wound up chains 5 will depend from the larger diameter of the cones, and when the receptacle is raised and the springs uncoil the chains will wind on the cones and depend from the smaller diameter thereof, whereby compensation is made for the varying strength of the springs 6^a. Considerable load may be carried in receptacle 4 when the latter is elevated without requiring undue pull upon the receptacle to depress it, the increasing diameter of the winding-chain on the cones compensating for the increasing tension of the springs. The tension of the springs 6^a with respect to the varying diameters of the cone-pulleys may be such that when the receptacle 4 is pulled down to its 8c lowest point it will hang in such position by reason of the leverage of the larger diameter of the cones with respect to the tension of the springs 6^a, and so that when the chains 5 depend from the smaller diameter of the cones the reduced leverage of the small diameter of the cones with respect to the tension of the springs then partly uncoiled will substantially equalize and permit the receptacle with its load to remain in the ele- 90 vated position.

To the rollers 6, as near one end, I attach gear-wheels 8, that mesh with gears 9, (shown mounted to rotate upon the rods 3,) and the chains 5 pass over the outer sides of cones 7, 95 whereby the cones and rollers 6 will rotate in opposite directions and the gear 8 9 serve to balance the tension of springs 6^a in the rollers and cause the rollers to rotate equally, so that the chains 5 will wind equally and 100 simultaneously upon their respective cones.

In order to keep receptacle 4 from swaying while the carrier is traveling along its track, I provide the lower ends of the end members 1^a of the carrier-frame with angularly-shaped blocks 10, the angles of the

blocks facing the corners of receptacle 4, so as to receive the corners of the receptacle, as shown in Fig. 2, when the receptacle is elevated, and by preference the lower edges of blocks 10 will be made flaring for convenient entrance of the corners of the receptacle into the angles of blocks 10.

At 11 is a handle or grip on the bottom of receptacle 4 to enable the receptacle to be readily pulled down. As the receptacle should preferably travel above the heads of persons in a store when the carrier is used in a store-service apparatus and as employees of short stature may not conveniently reach handle 11, I provide the receptacle with a movable handle 12, which is normally held in a horizontal position below the receptacle, being pivotally supported, as at 13, upon handle 11 and provided with a spring 14, connected with the bottom of the receptacle, and with an extension 15 on handle 12, whereby the spring may normally keep the handle 12 raised. A cord or flexible connection 16 depends from the handle 12 in convenient position to be grasped by a short person, so that by pulling down on the cord the handle 12 can be swung down and then used to depress or elevate receptacle 4.

While I have shown the carrier-frame provided with two spring-rollers having tapering cones receiving chains 5, it will be understood that the carrier-frame may be provided with one or more such spring-rollers having tapering cones for connection with a receptacle according to the character and weight of the packages intended to be transported by the carrier.

My invention is not limited to the details of construction shown and described, as they may be varied without departing from the spirit thereof.

Having now described my invention, what I claim is—

1. A carrier comprising a frame, a roller provided with a spring carried by said frame, said roller having cone-like pulleys, a receptacle, and flexible connections connecting

said cone-like pulleys with the receptacle and adapted to wind spirally on said pulleys.

2. A carrier comprising a frame, a pair of rollers provided with springs carried by said frame, said rollers having cone-like pulleys at opposite ends, a receptacle, and flexible connections connecting said cone-like pulleys with the receptacle and adapted to wind spirally on said pulleys.

3. A carrier comprising a frame, a pair of rollers provided with springs carried by said frame, said rollers having cone-like pulleys at opposite ends, a receptacle, flexible connections connecting said cone-like pulleys with the receptacle and adapted to wind spirally on said pulleys, and gearing connecting said rollers, whereby they will rotate in unison.

4. A carrier comprising a frame, rollers carried by said frame provided with coil-springs, cone-like pulleys attached to the ends of the rollers, a receptacle, and flexible connections connecting the pulleys with the receptacle, the flexible connections depending from the larger diameter of the pulleys when the receptacle is pulled down and the springs thereby wound, said flexible connections depending from the smaller diameter of the cones when the receptacle is raised and the springs unwound.

5. The combination of a carrier-frame, a receptacle carried thereby, a handle movably attached to the receptacle, a spring connecting the handle with the receptacle to maintain the handle normally elevated, and a cord depending from the handle, whereby the handle may be extended downwardly when the receptacle is to be raised or lowered.

6. A carrier comprising a frame, a roller provided with a spring carried by said frame, said roller having cone-like pulleys provided with spiral grooves, a receptacle, and flexible connections connecting said pulley with the receptacle.

GUSTAV STAIB.
